PHONOGRAPH TURNTABLE DRIVE

William A. Schmittgen, Elyria, Ohio, assignor to
The General Industries Company, Elyria, Ohio,
a corporation of Ohio

Application November 27, 1935, Serial No. 51,878

4 Claims. (Cl. 274—39)

This invention relates to phonograph mechanisms and particularly to means for supporting and driving the turntables thereof.

The turntables of phonographs and the like are commonly driven by an electric or other motor and the speed of the motor is stepped up or stepped down by a gear type transmission. The torque applied by the motor to the turntable therefore is undulating in character, the torque while continuous having wave-like variations therein caused by the successively engaging and disengaging teeth of the gears in the transmission.

Furthermore, vibrations in the motor and transmission mechanism are transmitted through the shaft to the turntable supported on the shaft. Both of these types of vibrations, transmitted to the turntable, modify and distort to greater or lesser degree the sound record reproduced from the record supported on the turntable.

It is therefore an object of this invention to provide an improved means for supporting and turning the turntable of a phonograph or the like which will prevent transmission to the turntable of vibrations of the driving mechanism.

Another object is to provide, in connection with the turntable shaft of a phonograph or like mechanism, means for absorbing variations of torque and longitudinal and lateral vibrations of the shaft.

Another object is to provide an improved phonograph or like turntable drive.

Another object is to provide an improved phonograph or like turntable support.

Other objects will be apparent to those skilled in the art to which my invention appertains.

My invention is fully disclosed in the following description taken in connection with the accompanying drawing, in which:

Fig. 1 is a side elevational view with parts broken away of a turntable drive embodying my invention;

Fig. 2 is a sectional view taken approximately from the plane 2—2 of Fig. 1;

Figs. 3, 4 and 5 are, respectively, plan, front elevational and side elevational views illustrating separately an element shown in combination with other elements in Fig. 1;

Figs. 6, 7 and 8 are, respectively, plan, front elevational and side elevational views of another element separately shown.

Referring to the drawing, I have indicated generally at 1 a housing within which is contained a driving motor and transmission gears

for driving a vertical turntable shaft 2, illustrated as projecting upwardly out of the housing 1.

A pin 3 extends diametrically through the shaft above the housing 1, preferably being driven into a hole in the shaft.

A metal clutch washer 4, rests upon the pin 3, the washer having a central perforation 5 upwardly through which the shaft 2 is telescoped. The washer 4 has, at diametrically opposite portions thereof where it rests upon the pin 3, pairs of downwardly projecting lugs 6—6 engageable with opposite sides of the opposite end portions of the pin 3. Thus the lugs 6—6 provide, in effect, notches the sides of which embrace opposite end portions of the pin whereby rotation of the shaft 2 will positively be transmitted to the washer 4. The lugs 6—6 may suitably be pressed out of the metal of the washer 4 as plainly illustrated in the drawing.

Resting upon the upper side of the washer 4 as viewed in Figs. 1 and 2, is a cushioning washer 7 of suitable cushioning or vibration-absorbing material such as rubber. The washer 7 is preferably of the same diameter as the washer 4 and has a central perforation 8 therethrough substantially fitting the shaft 2 telescoped through the perforation. The cushioning washer 7 is provided with a pair of diametrically opposite perforations 9—9 into which project teeth 10—10 extending upwardly from the washer 4. The teeth 10—10 are preferably formed by pressing them out of the material of the washer 4.

Upon the upper side of the cushioning washer 7 is a pair of clutch teeth 11—11 extending in alignment diametrically across the cushioning washer and preferably formed integrally therewith. The clutch teeth 11 are wedge-shape in cross-section as plainly shown in Fig. 1 having inclined sides 12—12.

The turntable 13 is provided with a hub 14 on the underside thereof and secured thereto in any suitable manner, for example by being riveted thereto by means of a flange 15. The hub 14 is preferably of substantially the same diameter as the washers 4 and 7 and has a bore therethrough for telescoping it over the shaft 2. The lower face of the hub 14 rests upon the upper face of the cushioning washer 7 and is provided with diametrically aligned clutch recesses 16—16, the sides of which are tapered to substantially coincide with the inclined sides 12—12 of the clutch teeth 11.

In the operation of the embodiment of my invention illustrated, when the motor in the

housing 1 is operated to turn the shaft 2, the pin 3 on the shaft engages the lugs 6-6 and turns the washer 4, which in turn, by means of the teeth 10-10 in the perforations 9-9, turns the cushioning washer 7 and it in turn, by means of the clutch teeth 11 and clutch recesses 12, turns the hub 14 and through it the turntable 13.

Vibrations in general in the shaft 2 are absorbed, before reaching the hub 14 and turntable 13, by the cushioning washer 9. Rotational or torque irregularities and undulations are absorbed partly by the friction between the cushioning washer 7 and the lower end of the hub 14 resting thereon and partly by the toothed engagement of the cushioning washer 7 with the hub 14.

The tooth-and-recess engagement at 12-16 provides a positive drive for the turntable from the shaft 2, but at the same time a yielding or cushioned drive.

By sloping the faces 12 of the rubber clutch tooth 11 and the corresponding faces of the recesses 16, there will be a maximum amount of torque at which the turntable 13 will be lifted and the clutch tooth 11 will ride thereunder. This slipping amount of torque may be predetermined to be far in excess of that required to normally drive the turntable at any time, but provides for slipping of the drive, so that if a careless operator should by hand give a powerful spinning movement to the turntable, the force of such spinning movement will not be transmitted through the shaft to the gearing and to the motor and cause undue wear or injury thereto.

In the embodiment illustrated, the cushioning washer 7 is driven by the teeth 10 and perforations 9. If desired, the teeth 9 and the perforations may be omitted and the cushioning washer 40 7 secured to the upper side of the disc 4 in the position illustrated by vulcanizing or by any suitable adhesive.

My invention is not limited to the exact details of construction shown and described. Changes 45 and modifications may be made within the spirit of my invention without sacrificing its advantages and within the scope of the appended claims.

I claim:

1. In a phonograph mechanism of the type comprising a vertical drive shaft and a turntable having a hub telescoped over the shaft, a support and drive for the hub comprising a pin extending through the shaft, a metal disc telescoped on the shaft resting on the pin, a tooth on the disc engaged by the pin to rotate the disc with the shaft, a rubber washer telescoped on the shaft and resting on the metal disc, mutual inter-engaging means on the disc and washer whereby the washer will be rotated with the disc, the hub resting on the rubber washer, a pair of opposite toothed recesses in the hub and a pair of rubber teeth integral with the rubber washer projecting into the toothed recesses.

2. A mechanism as described in claim 1 and in which the toothed recesses have opposite upwardly converging faces permitting disengagement of the hub and washer by a torque action 20 overcoming the weight of the parts supported by the washer.

3. In a phonograph mechanism of the type comprising a vertical drive shaft and a turntable telescoped over the shaft, a support on the shaft 25 for the turntable, and means to rotate the turntable by the shaft comprising mutually engaged projection and recess means, one on the support and the other on the turntable and one composed of rubber or like cushioning material, and said projection and recess means being disengageable upon the occurrence of a torque action 30 overcoming the weight of the turntable.

4. In a phonograph mechanism of the type comprising a vertical drive shaft and a turntable 35 telescoped over the shaft, a support on the shaft for the turntable, and means to rotate the turntable by the shaft comprising mutually engaged projection and recess means, one on the shaft and the other on the turntable and the projection means being formed from rubber or like cushioning material, said engaged means being ineffective to rotate the turntable upon the occurrence of a torque action sufficient to overcome 40 the turntable weight.

WILLIAM A. SCHMITTGEN.
